UNITED STATES PATENT OFFICE.

THEODORE S. WILKIN, OF MILWAUKEE, WISCONSIN.

LOG-TURNER.

SPECIFICATION forming part of Letters Patent No. 415,315, dated November 19, 1889.

Application filed July 11, 1889. Serial No. 317,114. (No model.)

To all whom it may concern:

Be it known that I, THEODORE S. WILKIN, a citizen of the United States, residing at Milwaukee, in the county of Milwaukee and 5 State of Wisconsin, have invented certain new and useful Improvements in Log-Turners, of which the following is a specification.

My invention relates to that class of devices for transferring the log from the log-way onto the carriage, and has reference more particularly to those employing steam, air, or other fluid under pressure for the purpose of actuating the different parts of the machine.

15 In the drawings, Figure 1 is a top plan view illustrating the general arrangement of the logway, carriage-track, and saw-mill; Fig. 2, a vertical sectional view at right angles to the line of travel of the carriage; Fig. 3, a face 20 view, partly in section.

A indicates the general frame-work of the mill; B, the log way; C, the saw-mill carriage; D, the saw, and E the floor of the mill. As the construction and arrangement of these form 25 no part of the present invention, they may be modified, as found necessary or desirable.

F indicates the toothed bar, that is designed to project up through the floor and engage the log on the logway and to raise it from its 30 seat therein and roll it onto the saw-mill carriage.

G indicates a cylinder secured in a horizontal position on the floor directly in line with the bar F, as shown in Fig. 1. This cylinder 35 is provided with a valve-stem a, (shown in Fig. 1,) which in turn is connected with an elbow-lever b, carried at the upper end of an upright shaft c, having at its lower end a second elbow-lever d.

40 The piston-rod H of the cylinder G is provided at its forward end with an open frame or block I, having lateral ribs or flanges e, as shown in Fig. 3, the ribs or flanges projecting into the grooved faces of the guides J, secured to the floor, as shown. Block or frame I is adapted to receive and guide the bar F, and upon reference to Fig. 1 it will be seen that the side arms of the block are each provided with a small wheel or roller f to enter 45 the sides of the bar, which are recessed to receive them. This construction permits the

bar to rise and fall relatively to the guiding-block, but at the same time prevents the bar from escaping. The bar will be inclined at times, and to afford a bearing for it and to 55 relieve the wheels or rollers f f of undue strain the said block or frame is provided with a roller g, which is designed to support the rear face of the bar. If steam be admitted to the front end of the cylinder G, the rod 60 H will be retracted, and as the frame or block I is secured to the piston-rod, and as the wheels f f of the block enter into the recessed sides of the bar, it will be seen that the bar will move the piston-rod. If steam be admitted to the rear end of the cylinder, the piston-rod and the bar will be carried forward, the 65 position of the bar depending upon that of the piston-rod to which it is attached.

The lower end of the toothed bar F is pivoted to the upper end of the piston-rod of an upright cylinder K, which latter is provided with a valve-stem h, by actuating which the induction and excretion of steam are controlled. Cylinder K is provided at its lower 75 end with lateral trunnions i, as usual in this class of devices, and is supported upon a base plate or bed j, as shown in Fig. 2. A link or rod L, secured at one end to the frame-work and at the other to the bar F, steadies the 80 movements of the latter and limits the swinging or oscillating of the cylinder. The valve-stem h of cylinder K is connected by a rod k with one arm of an elbow-lever l, pivoted to the frame-work, the other arm of said elbow- 85 lever being connected, by means of a rod m, with the lower end of a controlling-lever M, as shown. Elbow-lever d, before referred to, is connected, by means of a rod n, with an elbow-lever o, which in turn is connected 90 with the lever M by a rod P, as shown. The lever M is mounted upon a universal joint q, of any desired construction, the joint being so arranged as to permit the lever to be swung backward and forward, or to either side, as 95 desired. When it is desired to roll the log onto the carriage, the lever M is moved in the direction indicated by the arrow in Fig. 2, and as the lever is connected with the valve-stem (through the connections b c d n o p) 100 the latter and the valve attached thereto will be moved so as to admit steam to the front

end of the cylinder G. Of course this will cause the piston-rod H to move into the cylinder, and as it thus moves inward it retracts the block or frame I, and also the upper end 5 of the bar F. As soon as the bar F has assumed the desired inclination the lever M will be brought back to its normal position, and (by means of the intermediate connections b c d n o p) the further movement of 10 the piston-rod prevented. Now by moving the lever M in the direction indicated by arrow in Fig. 3 the valve-stem h of cylinder K will be operated (through connections k l m) and steam admitted to the lower end of the 15 cylinder, the steam thus admitted serving to actuate the bar F—that is, raises the latter so that it will project upward behind the log on the logway. If lever M be now moved so as to admit steam to the rear end of the cylinder G, the upper end of the bar will be carried forward so as to roll the log from the logway onto the carriage. The two movements of lever M are independent of each other, so that when the lever is moved to operate valve-stem a of cylinder G the valve- 20 stem h of cylinder K will not be affected, and vice versa. It will be noted that the cylinder G is located in such position as to secure the best possible results, the direct thrust given 25 to the upper end of the bar in throwing the log onto the carriage relieving the parts of the twisting and straining to which they would otherwise be subjected. The cylinder K is also arranged with particular reference 30 to the work it has to perform, and it will be seen that as its piston-rod acts directly upon 35 the end of the toothed bar the best results are secured.

Compressed air or any other fluid under 40 pressure may be substituted for steam.

The guide-block may be grooved, if desired, and the guides J provided with the flanges e; but as this is merely a reversal of the arrangement shown it is not deemed necessary to illustrate it. 45

Bar F need not necessarily be toothed, the teeth serving only to take a hold upon the log when it is desired to turn the same.

Having thus described my invention, what 50 I claim is—

1. In combination with the toothed bar, a cylinder K, provided with a piston connected with the lower end of the bar, a cylinder G, having a piston that is connected with the 55 upper end of the bar, and means for controlling the admission of a fluid under pressure to the cylinders.

2. In combination with the toothed bar F, an upright cylinder K, a piston working within the same and having its rod connected 60 with the bar, a horizontal cylinder G, and a piston working therein and having its rod connected with the upper end of the bar.

3. In a log-turner, the combination, with the reciprocating bar, of a guide for the upper end of the same, and means for moving the guide positively, backward and forward, away from and toward the log-carriage, all substantially as shown. 65

4. In a log-turner, the combination, with 70 the reciprocating bar pivoted at its lower end, of a laterally-moving guide for the bar applied to the upper end of the latter, and means for moving the guide and bar positively, backward and forward, away from and 75 toward the log-carriage, all substantially as shown.

5. In a log-turner, the combination, with the reciprocating bar pivoted at its lower end and actuated by a fluid under pressure, 80 of a guide for the bar, also actuated by a fluid under pressure.

6. In a log-turner, the combination, with the reciprocating bar F and means for reciprocating it, of a cylinder G in line with and 85 in rear of the upper end of the bar, and a piston-rod H, working within the cylinder and connected with the bar.

7. In a log-turner, the combination, with the grooved or recessed bar F and means for reciprocating the same longitudinally, of a 90 guide block or frame I, provided with rollers f f, to enter the grooved sides of the bar, and means for actuating the guide-block.

8. In a log-turner, the combination, with 95 the grooved or recessed bar F and means for imparting a longitudinal movement thereto, of a guide-block I, provided with rollers f f, to enter the grooves in the bar, and with a roller g, to bear against the rear face thereof, 100 and means for operating the guide-block.

9. In a log-turner, the combination, with the grooved bar F and means for reciprocating the same, of a guide-block I, provided 105 with lateral flanges e e and rollers f f, grooved guides J J, adapted to receive the guide-block, and means for reciprocating the guide-block.

In witness whereof I hereunto set my hand in the presence of two witnesses.

THEODORE S. WILKIN.
